CLAIM

The ornamental design for a combined display and storage case for pens and the like, substantially as shown and described.

DESCRIPTION

FIG. 1 is a perspective view of a combined display and storage case for pens and the like showing my new design;

FIG. 2 is a front elevational view thereof;

FIG. 3 is right side elevational view, the left side being a mirror image thereof;

FIG. 4 is top plan view taken in the direction of the arrows in FIG. 3;

FIG. 5 is a bottom perspective view thereof; and

FIG. 6 is rear elevational view thereof.

Fig. 2.

Fig. 4.

Fig. 6.
